FISHING ROD HOLDER

John B. Bennett and Leonard L. High, both of 751 S.
Sherman St., Richardson, Tex. 75080

Filed July 29, 1969, Ser. No. 18,450

Term of patent 14 years

Int. Cl. D22—08

U.S. Cl. D22—22

The figure is a perspective view of a fishing rod holder showing our new design.

Both sides of the fishing rod holder are identical.

We claim:

The ornamental design for a fishing rod holder, substantially as shown and described.
